Primary Examiner — Austin Murphy*(74) Attorney, Agent, or Firm* — Lisa P. Fulton; Irina Hass(57) CLAIM

The ornamental design for a tape dispenser, as shown and described.

DESCRIPTION

FIG. 1 is a perspective view of a tape dispenser showing the new design;

FIG. 2 is a side view thereof, the opposite side being a mirror image;

FIG. 3 is a top view thereof;

FIG. 4 is a bottom view thereof;

FIG. 5 is a front view thereof;

FIG. 6 is a rear view thereof; and,

FIG. 7 is an alternate view of FIG. 1 showing the front and side views as transparent for the purpose of clearly depicting the dispensing mechanism and inner contours of the tape dispenser. This view is not an additional embodiment.

The broken line showing of a roll of tape is for illustrative purposes only and forms no part of the claimed design.
